(57) **CLAIM**

The ornamental design for a shoulder bag, as shown and described.

DESCRIPTION

FIG. 1 is a front perspective view of the shoulder bag;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is front perspective view of the shoulder bag of FIG. 1 in an open position.

The broken lines showing a shoulder bag are included for the purpose of illustrating environment and form no part of the claimed design.
